UNITED STATES PATENT OFFICE.

LEWIS B. VAN LEUVEN AND HARRY C. VAN LEUVEN, OF WOODBURY, NEW JERSEY,
ASSIGNORS TO VACUUM OIL COMPANY, OF NEW YORK, N. Y., A CORPORATION OF
NEW YORK.

FOAM COMPOSITION FOR EXTINGUISHING FIRES.

No Drawing.

Application filed November 9, 1922, Serial No. 599,913.

To all whom it may concern:

Be it known that we, LEWIS B. VAN LEUVEN and HARRY C. VAN LEUVEN, citizens of the United States, and residents of Woodbury, in the county of Gloucester and State of New Jersey, have invented certain new and useful Improvements in Foam Compositions for Extinguishing Fires, of which the following is a specification.

10 This invention relates to compositions or compounds of the kind that are used for extinguishing a fire or protecting a substance from fire, and especially to that class of compositions wherein a mixture of the ingredients produces a viscous foam, adapted particularly to smother and extinguish flames produced by ignited petroleum or other kinds of inflammable liquids, by excluding the air therefrom in such a way as to cut off 20 the supply of oxygen from the flames, by a blanket of foam containing a non-inflammable gas in finely divided bubbles. This blanket must be sufficiently heavy to withstand the rising draught caused by the heat 25 of combustion.

The fire extinguishing compounds of the type to which we refer are of two main constituents, the one a saline solution containing some chemical from which carbon dioxide gas can be liberated by the action of 30 the second solution, which is of a mildly acid character, such as a solution of aluminum sulfate. The action of liberating the gas loses its smothering effect unless this gas 35 is trapped and held to form a blanket-like foam in the solution mixture, which must be also of sufficient consistency to withstand heat. We make use of several well-known 40 agents to produce this effect; aluminum sulfate, saponin (quillaya bark extract), quebracho extract and sodium bicarbonate. We considerably improve and increase the efficiency of the foam by the admixture of a 45 strong alkali, such as caustic soda, to the solution containing the quebracho extract, saponin and sodium bicarbonate which prevents the coagulation and settlement of the various insoluble heavy "reds" in the quebracho extract, which are rapidly flocculated in the 50 presence of sodium bicarbonate. These "reds", if allowed to settle out, soon form a pasty sludge in the bottom of the mixing

tank and not being blended with the other ingredients in the mixture would do away with the greatly desired toughness and tenacity of the foam.

The object of our invention is to produce a tenacious, foaming mixture from certain chemical solutions, which neither deteriorate nor change in composition upon standing ready for use, and at the same time, are inexpensive, easy to mix, and require no particular skill in blending.

For the purpose of illustrating a practical application of our invention solutions having formulæ as follows may be used: Solution A to consist of 90 parts of water and 10 parts of aluminum sulphate; solution B to consist of 5 parts of quillaya bark extract, 5 parts of quebracho extract, 9 parts of sodium bicarbonate, and 81 parts of water. This solution B is made alkaline by the admixture of one-tenth to two-tenths of a pound of caustic soda per gallon of solution. This admixture will vary with the alkalinity of the constituents. The quebracho extract is any commercial grade of so-called "reds" from tanning liquors. Quillaya bark extract is the syrup formed by digesting $\frac{1}{2}$ pound of quillaya bark for eight hours with one gallon of boiling water.

We do not confine ourselves however to the above proportions.

What we claim as our invention and desire to secure by Letters Patent is:

1. A composition for use in connection with a solution of a mildly acid character, for extinguishing fire, consisting of sodium bicarbonate, quebracho extract, quillaya bark extract, sufficient quantity of the ingredients being used to produce a foam and kept in complete solution in water by the admixture of not less than 0.15% of caustic alkali.

2. A composition for use in connection with a solution of a mildly acid character, for extinguishing fire, consisting of sodium bicarbonate, quebracho extract, quillaya bark extract, sufficient quantity of the ingredients being used to produce a foam, and kept in complete solution in water by the admixture of not less than 0.15% sodium hydroxide.

LEWIS B. VAN LEUVEN.
HARRY C. VAN LEUVEN.
